CLAIM

The ornamental design for an elastomeric cover for a radiotelephone with an externally accessible port, as shown and described.

DESCRIPTION

FIG. 1 is a front view of an elastomeric cover for a radiotelephone with an externally accessible port showing my design illustrated in the environment of a radiotelephone; FIG. 2 is a back view thereof; FIG. 3 is a right side view thereof; FIG. 4 is a left side view thereof; and, FIG. 5 is a perspective view thereof.

The inside of the cover forms no part of the claimed design. The broken lines shown herein are for illustrative purposes only and form no part of the claimed design.
